UNITED STATES PATENT OFFICE.

LEVI HAAS AND DENNIS HOWARTH, OF CHESTER, PENNSYLVANIA.

FELT ROOFING.

SPECIFICATION forming part of Letters Patent No. 296,163, dated April 1, 1884.

Application filed January 7, 1884. (No model.)

To all whom it may concern:

Be it known that we, LEVI HAAS and DENNIS HOWARTH, citizens of the United States of America, residing at Chester, in the county of Delaware and State of Pennsylvania, have invented certain new and useful Improvements in Felt Roofing, of which the following is a specification, reference being had therein to the accompanying drawing.

10 Our invention relates to an improvement in felt roofing; and it consists both in the process of preparing the roofing material, and in the method of securing to the sheathing sheets or strips of the material thus prepared, to form 15 a water-proof roof, substantially as hereinafter more fully shown and described.

In the drawing, the figure is a plan view, showing the method of securing the roofing-sheets.

20 In carrying out our invention, we employ strips of tarred paper, A, each of which we perforate, as shown, near one of its longitudinal edges, and gradually fasten them upon the sheathing-boards of the roof, and as they are 25 fastened to the sheathing suitable roofing-cement is applied to them, which passes through said perforations and becomes cemented to the sheathing-boards, thus holding each strip or sheet rigidly in position. The first strip is laid 30 flat upon the sheathing near the edge of the roof, and the second sheet is lapped over the first sheet and the perforations thereof, and the third in like manner as the second, and so continuously *seriatim*. The felting is thus laid in 35 order to avoid the use of nails and strips for fastening it down, and the leakage which arises

from gradually-enlarging nail-holes, due to expansion and contraction of the strips. Thus secured, the felting is in condition to receive the surface or finishing coat B, which consists 40 of a mixture of broken pebbles and roofing gravel.

Other substantially similar articles may be substituted for pebbles, such as crushed quartz, limestone in its manifold varieties, the 45 crushed slag of furnaces, or broken rock; but where roofs are walked upon, pebbles are preferred as least likely to cut the cement when sustaining the weight of pedestrians.

Having described our invention, what we 50 claim is—

1. A roofing consisting of the tarred-paper strips A, having perforated longitudinal edges cemented to the sheathing, the first sheet being laid flat upon the sheathing, and the second lapped over the perforations thereof, the third being in like manner lapped over the 55 perforations of the second, and so continuously *seriatim*, and a surface or finishing coat, substantially as shown, and for the purpose 60 described.

2. In a roofing, the tarred and perforated strips A, cemented to the sheathing and coated with a mixture of broken pebbles and gravel, 65 for the purpose described.

In testimony whereof we affix our signatures in presence of two witnesses.

LEVI HAAS.

DENNIS HOWARTH.
